UNITED STATES PATENT OFFICE

PAUL O. FARNHAM, OF BOONTON, NEW JERSEY, ASSIGNOR TO RADIO CORPORATION OF AMERICA, A CORPORATION OF DELAWARE

DYNATRON RECEIVER

Application filed October 17, 1931. Serial No. 569,422.

The present invention relates to receiving circuits, and more particularly to receivers utilizing a dynatron stage adapted for amplification or oscillation employment.

It is well known that a dynatron will act as a satisfactory oscillator when a tuned impedance of appropriate design, is included in the plate circuit of the dynatron. This accepted use of the dynatron as an oscillation generator has restricted the use of the arrangement as an amplifier to circuits employing an aperiodic plate load. This may be explained by the fact that the more usual design requirements for a tuned amplifier are freedom from oscillation, as well as freedom from marked variation in gain, as the amplifier is tuned over a range of frequencies. In the case of radio receivers employing two, or more, tuned amplifier stages in cascade, stability, sensitivity and selectivity of the receiver must be rigidly maintained under all operating conditions. Hence, when it was attempted in the past to employ the dynatron as a tuned amplifier, it was found that known methods of securing stability were not applicable to the dynatron.

However, in my copending application Serial No. 523,859, filed March 19, 1931, I have disclosed various methods of, and means for, securing stability of operation of a dynatron amplifier circuit including a tuned plate load impedance. From experimental and theoretical considerations, the following characteristics were developed:

When the magnitude of plate load of a tuned dynatron amplifier circuit is less than that of the plate resistance ($R_B < r_p$), the tube and associated circuits will operate satisfactorily as an amplifier. But, when the external impedance and plate resistance are equal ($R_B = r_p$), oscillation of the system is impending. Finally, when the load is of greater magnitude than the plate resistance ($R_B > r_p$), the system will oscillate. And, the oscillating condition could be attained either by adjusting the control grid bias toward less negative values, or by increasing the plate load.

For utilizing the dynatron as a stable tuned amplifier, the tendency to oscillate, due to

gain control or tuning, was overcome by means which compensated for control electrode bias variation and plate load change.

Now, I have devised a novel receiver arrangement, embodying and applying the aforesaid principles and observations disclosed in my said copending application. There are many situations where it is highly desirable to operate the same radio receiver as an instrumentality for receiving speech modulated waves, or chopped continuous waves employed in code transmissions. The change from speech to code reception should be effected, of course, with a minimum use of apparatus. According to the present invention such a receiver may be provided by utilizing a dynatron as a tuned radio frequency amplifier, when receiving speech modulated energy, and as an oscillation generator when receiving code signals.

It may, therefore, be stated that it is one of the main objects of the present invention to provide a radio receiver, capable of use for both code and speech signals, the receiver comprising at least one high frequency dynatron amplifier having a tuned plate load impedance, the amplifier including means for converting the amplifier into an oscillator without the addition of further apparatus.

Another important object of the present invention is to provide a receiver arrangement utilizing a dynatron amplifier having a resonant output circuit, the receiver including a device for maintaining an approximate constant ratio between the magnitude of the plate resistance and the plate load of a value to prevent oscillation when the receiver is employed for speech reception, said device being adapted for adjustment to enable said ratio to exceed unity when it is desired to operate the dynatron as an oscillator in the reception of code signals.

Still other objects of the present invention are to improve generally the simplicity and efficiency of combined broadcast and code radio receivers, and to particularly provide such a combined receiver which is not only stable when operating for speech reception, but converted into a code receiver in an economical and simple manner.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several arrangements for carrying my invention into effect.

In the drawing,

Fig. 1 shows, in diagrammatic manner, a radio receiver of the tuned radio frequency amplifier type embodying the invention,

Fig. 2 shows a superheterodyne type of receiver employing the invention.

Referring now to the drawing wherein like reference characters designate the same elements in the different figures, there is shown

in Fig. 1 a conventional radio receiver of the tuned radio frequency amplifier type, wherein a source 1, of speech modulated signal energy, is coupled at M to a tuned radio frequency amplifier stage. The latter may comprise a tetrode of the screen grid type employing an indirectly heated cathode, and is so conventionally represented on the drawing. The input of the stage is tuned by a variable condenser 2.

The output is impressed upon the tuned input of a second stage of radio frequency amplification, as at M₁. A variable condenser 3 is employed for tuning the second stage to resonance. The tube 4 of this stage may be a screen grid tube of the same type as in the first stage, the control grid 5 thereof being biased by means of the well known biasing network usually disposed in the grounded lead of the cathode 6. The network consists of a variable resistor 7 shunted by a by-pass capacity 8, variation of the magnitude resulting in change of the gain of the amplifier in a manner well known to those skilled in the art. The screen grid 9 is connected, by a lead 11, to the positive side of a source B, the grounded by-pass condenser 12 serving as a path for radio frequency currents.

The anode 10 of the tube 4 is connected to a point of less positive potential on source B through a path including in series the primary coil 13 of a twin winding transformer M₂, a variable resistor 14, and the adjustable tap 15. The negative side of the source B is grounded, while the grounded condenser 16 serves to by-pass radio frequency currents around the source B. The secondary coil 17, of the transformer M₂, is structurally included in the input circuit of the detector tube 18, of the same type as tube 4, the variable condenser 19 serving to tune the detector to resonance. The condensers 2, 3 and 19 are arranged for mechanical uni-control, as designated by the dotted lines 20, and as em-

bodied, for example, in the conventional type of bath tub gang condenser.

The control grid of the detector tube 18 is arranged for detection by providing in the negative lead of the cathode thereof the usual grid biasing network comprising the resistor 7' shunted by the condenser 8'. The anode of the detector tube is arranged to be positively biased from a source B', the lead between the source and the anode including the coupling resistor 21, the anode circuit of the detector tube being shown arranged for resistance-capacity coupling to the input of an audio frequency amplifier, not shown. It will be understood that subsequent to audio amplification of the detected energy, the amplified audio energy may be utilized in head-phones, a loud speaker, or any other utilizing means well known to those skilled in the art.

The screen grid of the detector tube 18 is arranged for positive biasing from a source S, the positive potential of the screen grid being, of course, considerably less than that applied to the anode of the detector tube, as is well known to those skilled in the art. The condensers 12' and 16' are employed to bypass radio frequency currents around the screen grid and anode leads.

When the receiver circuit shown in Fig. 1 is employed for the reception of speech modulated, or radio broadcast, signal energy the variable resistor 7 is employed as the gain control mechanism of the receiver. It has already been pointed out heretofore that when the tube 4 is arranged to function in a dynatron circuit (that is when the screen grid has a much higher positive bias than the anode), and the plate load of the tube comprises a tuned impedance, there will be a tendency towards oscillation upon adjustment of the control grid bias towards less negative values, or upon increase of the plate load.

Hence, when the dynatron stage is to be operated as a tuned radio frequency amplifier, as is desired when receiving speech modulated energy, it is essential that some device be employed for constantly overcoming the tendency of the dynatron stage to oscillate when the gain control mechanism is adjusted, or when the tuned plate load impedance is varied, as when the output circuit of the dynatron amplifier is varied with respect to resonance.

In my aforementioned copending application it has been pointed out, as stated heretofore, that when the plate load of the dynatron amplifier is less than the plate resistance, the tube and associated circuits will operate satisfactorily as an amplifier. Thus, in the said copending application the tendency to oscillate, if an electrode voltage was adjusted to increase the amplification, was overcome by a simultaneous and automatic adjustment

of another electrode voltage. Specifically, this was accomplished by introducing into the plate circuit of the dynatron amplifier a resistance of such value, when the amplification rate was controlled by varying the control grid bias, that the plate potential varied with grid bias to avoid conditions favorable for oscillation at any gain control adjustment of the grid bias.

One specific arrangement whereby this was accomplished in my copending application is shown in Fig. 1, it being clearly understood that this specific arrangement is merely shown by way of illustration, and that any other methods for overcoming the tendency to oscillate during gain control of a dynatron amplifier are shown in my copending application. The direct current potential from source B is impressed upon the plate 10 through a path, which includes the primary coil 13 of the twin winding transformer and the resistor 14, the path having an effective total resistance equal to the aforementioned plate resistance which is to be introduced into the plate circuit. The resistor 14 functions to increase the plate voltage, for a constant plate supply voltage determined by a desired position of the tap 15, as the control grid bias is reduced to increase the stage gain.

From an electrical point of view, and although the resonant circuit 17, 19 is disposed in the input circuit of the detector tube 18, the resonant circuit 17, 19 may be considered as a tuned impedance which acts as a load on the plate circuit of the dynatron amplifier. Of course, the value of the resistor 14 is so chosen, and may, for example, have a value of between 15,000 and 20,000 ohms, as to result in securing a stable operation throughout the variation of the gain control resistor 7.

Reverting to the question of freedom from oscillation if the resonant circuit 17, 19, which functions as the load of the dynatron plate circuit, is tuned over a band of frequencies, it is recognized that the impedance, at resonance, of a tuned circuit varies with the frequency to which the circuit is tuned. As the plate load impedance of the dynatron amplifier should vary widely with the tuning of the circuit 17, 19, these variations may so alter the magnitude of the load impedance that oscillatory conditions are established. Optimum conditions, so far as concerns stability of operation with tuning, may be obtained by maintaining a constant ratio between the magnitudes of the external plate load and the internal plate-cathode resistance of the tube. This condition may be realized by maintaining the plate load substantially invariant with tuning for a fixed plate resistance, or by varying the plate resistance as a substantially linear function of a varying plate load. The specific arrangement shown in Fig. 1, which comprises

the path including the resistor 14, functions therefore as a compensating or corrective network to carry out the first method which maintains the load impedance, as viewed from the plate and cathode terminals, substantially independent of the tuning of the output circuit. Thus, it will be seen that once a desired value of plate voltage supply has been determined by adjusting the tap 15 to a desired point, and the desired value of resistor 14 has been chosen for overcoming the tendency to oscillate when the gain of the dynatron stage is varied, or when the plate load is varied by tuning, then the tuned dynatron amplifier stage will be stable in operation.

It should be pointed out that the first radio amplifier stage may also comprise a tuned dynatron amplifier stage, and that the twin winding coupling transformer M_2 may be employed in place of the coupling M_1 . Furthermore, it is to be clearly understood that the resonant circuit 17, 19 may be disposed directly in the plate circuit of the dynatron amplifier, a twin winding transformer being employed for the sake of convenience in securing other desirable advantages which need not be mentioned herein. It is again pointed out that in my aforementioned copending application various other methods are disclosed for securing stability of operation, (that is overcoming tendency to oscillate, during gain control and tuning variation) and it is to be clearly understood that any of such methods for securing stability of operation may be employed herein in place of the specific arrangement shown.

When it is desired to receive code signals, that is to say code signals transmitted in the form of chopped continuous waves, it is merely necessary to allow the dynatron amplifier stage to oscillate. This may be accomplished by taking advantage of the observations already described. It is only necessary to vary the magnitude of the resistor 14 to such a value that it will fail to overcome the tendency for the dynatron amplifier to oscillate when the gain control resistor 7 is adjusted toward less negative values. Of course, it should be realized that similar instability may be secured by varying the position of tap 15 on the source B to a value proper for oscillation at weak amplitudes when receiving continuous waves. Variation of the resistor 14 to give a lower plate voltage will also result in oscillation. It will, therefore, be seen that there are at least three ways in which to convert the stabilized dynatron amplifier into an oscillation generator.

One of these ways consists in changing the magnitude of the stabilizing resistance 14 so that when the bias resistor 7 is adjusted to less negative values oscillations will be secured; another way consists in adjusting

the position of tap 15 to vary the potential applied to the plate 10; and still another way consists in varying the value of resistor 14 in order to lower the potential applied to the plate 10. The advantage of decreasing the plate potential, either by variation of the resistor 14 or by movement of the tap 15, consists in the fact that the dynatron stage then oscillates at such a part of its characteristic that the amplitude of oscillation can be modulated by the incoming signals, thus providing a carrier and side bands for the detector input voltage. Of course, other circuits could be varied to throw a stable dynatron amplifier stage into oscillation. In my aforementioned copending application additional variables have been disclosed which may be controlled to insure stability of a tuned dynatron amplifier, and, accordingly, 20 by varying these factors, oscillations may be produced.

An aperiodic reactive network is employed in the control grid circuit of the detector tube 18 to prevent overloading of the detector when the preceding dynatron stage is thrown into oscillation. The network preferably comprises a resistor 23 in series in the control grid circuit, the resistor being shunted by an audio frequency by-pass condenser 22. One of the important advantages secured by means of the present invention comprises the fact that detuning of the cascaded stages when a gang condenser is employed is not produced. Furthermore, the 35 use of a separate oscillator tube and a separate tuned circuit, which has been necessary to avoid detuning, is eliminated by means of the present invention.

In Fig. 2 there is shown in diagrammatic 40 manner a superheterodyne receiving circuit embodying the present invention. It is not believed necessary to point out the details of the circuit in Fig. 2 in specific manner, in view of the fact that the operation thereof 45 is substantially the same as the operation of the receiver shown in Fig. 1. It is merely believed necessary to point out that a multi-stage radio amplifier is coupled to the source 1, and the amplified radio frequency energy 50 is impressed upon the input of the usual first detector with energy from a local oscillator. The radio amplifier, first detector and local oscillator are arranged for uni-control tuning in the usual manner, such uni-control 55 arrangement being conventionally represented by the reference numeral 20', and shown as dotted lines connecting the variable condensers of each of these receiver elements. The intermediate frequency amplifier is 60 shown as comprising only a single tuned dynatron amplifier stage, and it is to be understood that the stage corresponds in every way to the second radio frequency amplifier stage of Fig. 1, with the exception that the 65 condenser 3' in the input of the tube 4 is

fixedly tuned to the intermediate frequency, instead of being arranged for adjustment as in the case of Fig. 1.

The second detector has its input arranged in substantially the same manner as the detector shown in Fig. 1, with the exception that the condenser 19' is maintained fixedly tuned to the intermediate frequency employed, instead of being adjustable as is the case with condenser 19 and the case of Fig. 1. When receiving speech modulated signal energy the superheterodyne receiver in Fig. 2 functions in the usual manner, the intermediate frequency amplifier being arranged for stable operation by adjusting the plate supply voltage to the desired constant value by means of the tap 15, and assigning to the resistor 14 the value necessary to overcome the tendency to oscillate when the gain control resistor 7 is adjusted to vary the amplification, it being understood that the variable resistor 7 functions as the gain control mechanism of the superheterodyne receiver.

When it is desired to receive code signals transmitted as continuous waves, it is merely necessary to utilize any of the three aforementioned methods for throwing the intermediate frequency amplifier into oscillation. Assuming, then, that the resistor 14 is varied to decrease the value of the plate voltage of the tube 4 of the intermediate amplifier, the tube will oscillate and function to feed into the second detector carrier oscillations of intermediate frequency, whose amplitude is modulated by the incoming signals, thus providing a carrier and side bands for detection. It will thus be seen that when the present invention is employed in a superheterodyne receiver, and when the receiver is employed for receiving continuous waves, the necessity for a separate oscillator between the first and second detectors is rendered unnecessary by throwing the intermediate frequency dynatron amplifier into oscillations.

While I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:

1. In a dynatron amplifier, the combination with an electron tube and means for applying to the elements thereof potential effective to give the same a negative plate resistance, of a tuned circuit connected to the plate electrode of the tube, means rendering the ratio of plate load impedance to plate resistance less than unity when amplifying speech modulated signal energy, said last means being adjustable to render said ratio greater

than unity when amplifying unmodulated carrier waves.

2. In a radio receiver, a dynatron amplifier including a tuned impedance in its output circuit, means for controlling the gain of the amplifier, means for stabilizing the amplifier against oscillation throughout adjustment of said gain control means, said stabilizing means being variable for rendering the amplifier unstable to convert it into an oscillation generator.

3. In combination, in a radio receiver, a high frequency amplifier, a detector coupled to the amplifier, said amplifier including a dynatron circuit provided with a resonant plate load in the output circuit of the dynatron, means for controlling the gain of the dynatron, a stabilizing means in the output circuit of the dynatron, and additional means for rendering the dynatron unstable to produce oscillations.

4. In a superheterodyne receiver, means for producing intermediate frequency energy, an intermediate frequency amplifier comprising a dynatron circuit provided with a resonant impedance in its output circuit, a detector having its input coupled to said resonant impedance, means for controlling the gain of said dynatron amplifier, means for preventing oscillation of said dynatron amplifier during variation of the gain control means, said oscillation prevention means being adjustable to render the dynatron amplifier unstable to produce oscillations when receiving continuous waves.

5. In combination, a high frequency amplifier and detector, said amplifier including a dynatron amplifier circuit in its last stage, means controlling the gain of said dynatron amplifier circuit, stabilizing means in the output circuit of the dynatron amplifier circuit, additional means rendering the dynatron unstable to produce oscillations, means in the detector circuit rendering said detector sensitive to the reception of amplified signals when the dynatron circuit is in a non-oscillating condition, and means in the detector circuit preventing overload of said detector when the dynatron circuit is put into an oscillating condition for the reception of chopped continuous waves.

6. In combination, a high frequency amplifier and detector, said amplifier including a dynatron amplifier circuit in its last stage, means controlling the gain of said dynatron amplifier circuit, stabilizing means in the output circuit of the dynatron amplifier circuit, additional means rendering the dynatron unstable to produce oscillations, means in the detector circuit rendering said detector sensitive to the reception of amplified signals when the dynatron circuit is in a non-oscillating condition, and means in the detector circuit preventing overload of said detector when the dynatron circuit is put into an oscillating

condition for the reception of chopped continuous waves, said last means comprising a resistor in the detector grid circuit, and an audio frequency by-pass condenser in shunt with the resistor.

7. In combination, a high frequency amplifier and detector, said amplifier including a dynatron amplifier circuit in its last stage, means controlling the gain of said dynatron amplifier circuit, stabilizing means in the output circuit of the dynatron amplifier circuit, additional means rendering the dynatron unstable to produce oscillations, means including a bias resistor in the detector cathode and an audio frequency by-pass condenser in shunt with the resistor, in the detector circuit rendering said detector sensitive to reception of amplified signals when the dynatron circuit is in a non-oscillating condition, and means in the detector circuit preventing overload of said detector when the dynatron circuit is put into an oscillating condition for the reception of chopped continuous waves.

8. In combination, a high frequency amplifier and detector, said amplifier including a dynatron amplifier circuit in its last stage, means controlling the gain of said dynatron amplifier circuit, stabilizing means in the output circuit of the dynatron amplifier circuit, additional means rendering the dynatron unstable to produce oscillations, means including a bias resistor in the detector cathode and an audio frequency by-pass condenser in shunt with the resistor, in the detector circuit rendering said detector sensitive to reception of amplified signals when the dynatron circuit is in a non-oscillating condition, and means in the detector circuit preventing overload of said detector when the dynatron circuit is put into an oscillating condition for the reception of chopped continuous waves, said last means comprising a resistor in the detector grid circuit, and an audio frequency by-pass condenser in shunt with the resistor.
